APPARATUS FOR ABRASIVELY TREATING
METAL ARTICLESRoy William Guite, Mishawaka, Ind., assignor to
The American Foundry Equipment Company,
Mishawaka, Ind., a corporation of Delaware

Application July 20, 1937, Serial No. 154,529

9 Claims.

(Cl. 51—9)

This invention relates to apparatus for abrasively treating metal articles and more particularly to such apparatus having an arrangement for removing abrasive and loosened foreign matter from the work-piece.

According to the present invention, the apparatus comprises suitable apparatus such as a belt conveyor or conveyors for advancing a work-piece along a predetermined path. One or more abrasive projectors are provided for projecting a stream of particles for cleaning or otherwise treating the work-piece. The projector preferably comprises a rotary centrifugal throwing wheel having means associated therewith for controlling the flight of the thrown particles. One or more auxiliary conveyors is disposed closely adjacent the path of the work-piece and is adapted to receive abrasive which rebounds from the top surface of the work-piece and conveys it away from the work-piece. Suitably shaped and arranged baffles are provided for assisting in directing the rebounding abrasive into the auxiliary conveyor or conveyors. A blower or air-blast device is provided which has a nozzle disposed closely adjacent the path of the top surface of the work-piece and of such shape that a blast of air is directed outwardly across the surface of the work-piece to remove therefrom any loosened rust, scale, or other foreign matter, as well as any particles of treating material which are not collected by the auxiliary conveyors.

An object of the invention is the provision of apparatus for cleaning or otherwise treating metal articles, which apparatus has associated therewith efficient and highly effective mechanism for removing from the work-piece any abrasive, loosened scale or other foreign matter so that the work-piece issues from the apparatus in condition for use or further treatment.

Another object of the invention is the provision of sheet cleaning and treating apparatus of a highly effective mechanism for removing spent abrasive from the work-piece and collecting and returning such abrasive for further use.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection

with the accompanying drawings forming a part thereof, in which:

Fig. 1 is a side elevational view of one form of apparatus constructed in accordance with the invention, certain of the parts being broken away and sectioned in order to illustrate the construction;

Fig. 2 is a top plan view of the apparatus, certain of the parts being broken away for convenience in illustration; and

Fig. 3 is a view showing a transverse section taken along line 3—3 of Fig. 1.

In the following description and in the claims, various details will be identified by specific names for convenience, but they are intended to be as generic in their application as the art will permit. Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

The apparatus is particularly well adapted for treating sheets, strips, plates and other flat metal members and for the purposes of illustrating the invention, sheet or strip treating apparatus is disclosed. However, it is to be understood that the invention is capable of application with many different types of work-pieces.

The apparatus includes a housing 1 of suitable construction having a front wall 2, rear wall 3, side walls 4 and 5 and a top wall 6. The housing is provided with a bottom 1 which preferably is formed with inclined portions which define a hopper for collecting spent abrasive, as will be described more in detail hereinafter.

An inlet 10 is provided in the rear wall 3 and an outlet 11 is provided in the front wall 2. An upwardly opening extension 8 projects from the front wall 2 and is associated with the main portion of the housing and the outlet 11 for a purpose which will hereinafter appear.

A conveyor is provided for advancing sheet, strip or other flat elongated material S through the housing. The conveyor preferably comprises an endless belt 15 trained over rotatable rolls 16 and 17 suitably mounted, as by shafts 18 and 19. The upper carry of the belt 15 is adapted to receive and support the sheet S so that the same extends through the inlet 10 and outlet 11. The belt 15 extends through the opening 11 in the front wall 2 and through an opening 20 provided

- for permitting the passage of the belt. It will be noted that the forward roll 18 is disposed in the extension 8 so that the adjacent portion of the belt supports a portion of the sheet therein.
- 5 A second belt 21 is trained over rotatable rolls 22 and 23 suitably mounted on shafts 24 and 25, which belt is positioned so that its lower carry bears against the top surface of the sheet and maintains the same in contact with the belt 15.
- 10 The roll 23 is disposed outside the housing and the belt 21 extends through the inlet 10 and through an opening 26. An idler roll 27 is mounted under the belt 21 in position to support the sheet S at a point beyond the end of the belt 15.
- 15 It will be noted that the belts 15 and 21 overlap somewhat at the rolls 17 and 22 whereby the belts grip the sheet S with sufficient friction to advance the sheet S through the housing when the belts are caused to travel.
- 20 Carried on the shafts 19 and 24 respectively are gears 28 and 29 which mesh and thereby mechanically connect the rolls 17 and 22; consequently, the belts 15 and 21 can be driven at the same speed.
- 25 A member, such as a pulley 14, may be carried on the shaft 18 and suitable driving means (not shown) may be connected thereto for driving the belts 15 and 21.
- 30 Mounted on the top wall 6 of the housing is an abrasive projector A for projecting a divergent stream of treating material into the interior of the housing and against the top surface of the sheet S on the conveyor. A somewhat similar 35 wheel B is mounted to project a somewhat similar stream of abrasive *b* against the lower surface of the sheet S at a point between the roll 17 and the idler roll 27.
- 35 Although the projectors A and B may take various forms, preferably they are of the centrifugal type having means associated therewith for controlling the direction of flight of the thrown treating material. Inasmuch as each of the wheels is substantially similar in construction, only the wheel A will be described in detail herein, it being understood that the portions of the wheel B which are not described are generally similar to the corresponding portions of the projector A.
- 40 The projector A includes a wheel 13 comprising a plurality of throwing blades 30 which extend in a generally radial direction from adjacent the periphery of the wheel and which terminate at points inwardly short of the center to provide a central space 31. Disposed in the space 31 is an impeller 32 having a plurality of radially directed vanes 33. Surrounding the space and the impeller 32 is a relatively stationary and independently mounted control member 34 having 45 one or more discharge outlets 35.
- 45 The blades 30 preferably are supported by one or more side wall members 36 and 37, one of which is carried on a hub 39 mounted on a rotatable shaft 40 which is journaled in stationary bearings 41. The impeller 32 preferably rotates with the blades and may be connected to the shaft 40. A motor 42 is suitably mounted, as for example, on the top wall 6, and is connected to the shaft 40 by a drive 43 for rotating the wheel 13.
- 50 The wheel extends through an opening 47 in the top wall 6 and may be provided with an enclosing casing 48. Baffles 49 may be provided 55 for forming a depending extension of the casing

48 and may be supported from the top wall 6 as by suitable brackets 50.

The wheel is supplied with treating material by a feed pipe 45 which extends through the housing 48 and leads to an opening 46 in the side plate 36 whereby the treating material is delivered to the impeller 32.

The treating material, sometimes referred to as "abrasive", may comprise granular material, such as cracked steel grit, steel shot, sharp quartz sand, or other cleaning, abrading, polishing or hardening material. The material selected will, of course, depend upon the surface effect desired. It will therefore be understood that where the term "treating material" or "abrasive" is used 15 it includes within its range all materials useful for cleaning, polishing, hardening or otherwise modifying the surface of metallic objects.

When the motor 42 is energized, it effects rotation of the wheel 13 and, when abrasive is 20 supplied to the wheel, the impeller 32 throws the abrasive through the opening 35 and into the path of the rotating blades 30. The abrasive is carried along the leading faces of the blades and is hurled therefrom adjacent the periphery 25 of the wheel at a velocity which depends upon the design and speed of the rotation of the wheel.

The abrasive is thrown from the wheel in a divergent stream which produces an elongated, generally rectangular, impingement pattern on a 30 plane passing below and substantially parallel to the axis of rotation of the wheel. The direction of flight of the treating material can be controlled by suitable adjustment of the clock dial position of the control member about the axis of 35 the wheel.

Preferably, the wheel is so designed and operated that the stream *a* of treating material terminates approximately at the longitudinal edges of the sheet S. Thus, the entire surface of the 40 sheet is subjected to the action of the treating material and all of the treating material is effective.

The projector B is suitably mounted below the sheet S in a suitable manner. Preferably, the shaft 40 extends through a suitable opening 52 in a recessed portion 51 of the rear wall 3 and the bearings 41 are mounted on a bracket 53. The shaft is rotated by a motor 42 connected to the shaft by a drive 43, as above described. The 50 feed pipe 45 may be supported by a suitable bracket 54 extending upwardly from the adjacent portion of the bottom wall 7. Preferably, no housing is provided since the wheel is otherwise enclosed by the housing 1.

The projectors A and B may be supplied with abrasive from a suitable storage hopper 60 having conduits 61 and 62 leading to the feed pipes 45 of the projectors A and B respectively.

The abrasive which is hurled by the projector B strikes the lower surface of the sheet S and falls by gravity into the hopper-like bottom 7 of the housing. If desired, a pair of baffles 75 and 76 are mounted on both sides of the abrasive stream *b* and adjacent the rolls 17 and 27 respectively to 65 protect the belt 15 and roll 27 from flying abrasive. One or more sets of flexible wipers 77 and 78 may be mounted adjacent the baffles 75 and 76, as shown particularly in Fig. 1, positioned to bear against the lower surface of the sheet S and thus prevent the rebounding abrasive from striking the belt 15 or the roll 27. If desired, the wiper or wipers 77 may be sufficiently rigid to scrape from the lower surface of the sheet S any loosened scale, rust or foreign matter so that the 70

same is not carried into contact with the belt 15.

The abrasive which is thrown by the projector A strikes the top surface of the sheet S and rebounds therefrom. Disposed adjacent the impingement pattern X of the stream A on both sides thereof are conveyors 65, 66 which extend transversely of the sheet S. The conveyors are preferably similar in construction and each includes an endless member, such as a belt 67 trained over rolls 68 and 69 carried on shafts 70 and 71 respectively. The belt 67 is mounted so as to engirdle the sheet S and the upper carry of the conveyor 15, the upper carry of the belt 67 being disposed closely adjacent the strip S. The lower carry of the belt 67 is disposed above the lower carry of the belt 15.

The conveyor members 67 may take any suitable form but it is preferable to give them such form that they receive and retain abrasive particles which have been disposed thereon. Therefore, preferably the rolls 68 and 69 are formed with arcuate peripheries which impart an arcuate cross-sectional shape to the belt 67, thus constituting in effect a transversely extending trough.

Disposed above the conveyors 65 and 66 and adjacent the projector A is a pair of baffles 72, 73 which diverge both laterally away from the projector A and upwardly away from a point closely adjacent the belt 15. The location and shape of the baffles are such that abrasive particles which rebound from the strip S strike the baffles and are directed into one or the other of the conveyors 65, 66. A baffle 74 extends from the conveyor 65 upwardly in position to further assist in directing abrasive into the belt 67 and a baffle 75' extends upwardly away from the conveyor 66: this baffle also serves to protect the belt 21 from flying abrasive.

The lower portion of the hopper-like bottom 7 is formed as a trough 79 which leads to an elevator 81; the front wall 2 is provided with an opening 9 to permit abrasive to pass from the extension and into the hopper-like bottom 7. Disposed in the trough 79 is a conveyor screw 80 carried on a shaft 97 for conveying the abrasive to the elevator.

The elevator 81 extends upwardly to the storage hopper 60 and is adapted to elevate the spent abrasive and deposit it in the storage hopper 60. The elevator 81 preferably comprises an endless belt 82 carrying lift buckets 83. The belt 82 is trained over drums 84 and 85 rotatably mounted by shafts 86 and 87. The elevator buckets may discharge into a cleaner 89 of suitable construction adapted to remove dust, dirt and other foreign matter from the spent abrasive. The cleaned abrasive then drops into the storage hopper 60 from whence it is supplied to the projectors as above described.

The several above-described portions of the apparatus which constitute the abrasive conveying apparatus, preferably are driven from a single source of power and are interconnected so that they are synchronized and abrasive is conveyed through the apparatus in a suitably controlled flow which is synchronized at its several portions. Thus, there is no opportunity for the abrasive to accumulate in undue quantity at any portion of its path of movement.

The driving apparatus comprises a motor 90 which may, if desired, drive a speed reducer 91 connected by a drive chain 92 to a sprocket 93 carried on the shaft 87. The shaft 87 is, as above described, connected by the belt 82 to the drum 84 carried on the shaft 86. The shaft 86

drives a sprocket 94 over which is trained a chain 95, also trained over a sprocket 96 carried on the conveyor screw shaft 97. The sprocket 94 also drives a chain 100 trained over a sprocket 101 which in turn is connected through gearing 102 to a sprocket 103. The sprocket 103 drives a chain 104 which is trained over a sprocket 105 carried on the shaft 70.

It will, therefore, be seen that when the motor 90 is energized it drives in synchronism the transverse conveyors 65 and 66, the control screw 80 and the elevator belt 82, whereby the spent abrasive is transported from the conveyors 65 and 66 to the storage hopper 60 in a suitably controlled, continuous and substantially synchronized flow.

Disposed above the upper carry of the conveyor belt 15 is a nozzle 110 of angular wedge shape. The nozzle is provided with an elongated outlet opening 111 disposed closely adjacent the upper surface of the sheet S at a point adjacent the forward edge of the transverse conveyor 65. The nozzle opening 111 is of V-shape with its apex approximately on the center line of the sheet S and diverging outwardly from rear to front of the housing, the outer ends of the opening extending slightly beyond the edges of the sheet S. The nozzle 110 extends through the front wall 2 of the housing and is located partially within the housing under the baffle 74 and partially in the extension 8.

A blast of air is provided by a suitable source of air pressure, such as a centrifugal pump 113 driven by a motor 114, which may be disposed on the top wall 6 of the housing.

One or more downwardly inclined baffles 115 may extend inwardly and downwardly from the sides of the extension to cooperate with the baffle 74 and adjacent portion of the front wall 2 for the purpose of preventing escape of dust, dirt, scale or abrasive material from the housing.

The operation of the apparatus is as follows:

The motors 42 are energized to rotate the wheels 13 of the projectors A and B and abrasive is fed to the wheels from the storage hopper 60. The projectors A and B thus project streams a and b downwardly and upwardly, respectively.

A sheet, strip or other flat, elongated piece of material is passed into the housing 1 through the inlet 10 and engaged with the belts 21 and 15. The belts 21 and 15 are driven from the pulley 14 in a manner above described and advance the sheet S through the housing and through the streams b and a, the former stream striking against the lower surface of sheet S and the latter stream striking against the upper surface of sheet S.

The spent abrasive thrown by the projector B drops into the hopper-like bottom 7, as described. The abrasive thrown by the projector A strikes the sheet S and rebounds therefrom, striking against either the baffle 72 or the baffle 73 from whence the abrasive rebounds and falls into either the conveyor 65 or the conveyor 66. Certain of abrasive will rebound from the baffles 74 and 75' and fall into the respective conveyors. The majority of the abrasive particles which are thrown by the projector A thus will be collected in the conveyors 65 and 66.

Conveyors 65 and 66 travel transversely of the housing and when the abrasive carried thereon reaches the end of the upper carry of the belts 67, 68, it drops therefrom and falls into the hopper-like bottom 7 and is collected in the trough 79.

The conveyor screw 80 urges the abrasive to the side of the housing and forces it into the elevator 81. The lift buckets 83 carry the abrasive to the top of the elevator and deposit it in the cleaner 89 from whence the cleaned abrasive drops into the storage hopper 60.

The blower motor 114 also is energized and drives the blower 113 which forces a blast of air through the nozzle 110. The air is ejected through the V-shaped opening 111 and passes laterally along the surface of the sheet S to the side edges thereof. The blast of air is of sufficient strength to force off the sheet S any abrasive particles which were not collected by the transverse conveyor 65 and 66 which remain on the sheet, as well as any loosened scale, rust and the like. Thus, when the sheet S passes beyond the extension 8, no abrasive particles or particles of scale, rust or foreign matter remain thereon.

20 The present invention provides apparatus whereby sheets, strips or other flat elongated pieces of material can be appropriately cleaned or otherwise treated and issue from the apparatus in fully cleaned condition and without carrying thereon any particles of abrasive, rust, scale or other foreign matter. The apparatus also insures that the abrasive particles are confined to the housing and are not carried therefrom by the sheet or strip.

30 The apparatus is substantially entirely automatic in operation and requires the minimum of attention on the part of an attendant. The several portions of the conveying mechanism for the abrasive are interconnected so that the abrasive is collected and transported in a substantially continuous, even and synchronized stream. Therefore, the opportunity for the abrasive to accumulate at any portion of the apparatus other than the intended portion, such as the storage hopper, is eliminated.

40 While certain novel features of the invention have been disclosed and are pointed out in the annexed claims, it will be understood that various omissions, substitutions and changes may be made by those skilled in the art without departing from the spirit of the invention.

What is claimed is:

1. Apparatus for cleaning and treating sheets, strips and like material comprising an abrasive projector for throwing a stream of abrasive particles over a predetermined path, a work-piece conveyor for advancing a sheet or strip through said stream of abrasive, means for removing spent abrasive, including an endless belt engirdling said work-piece conveyor and the sheet or strip carried thereon, and baffle means for directing rebounding abrasive on to said belt.

2. Apparatus for blast cleaning and treating metal sheets, strips and the like comprising, a substantially horizontally extending work-piece conveyor, a rotary centrifugal throwing wheel operative to project abrasive particles at blasting velocities in a controlled downwardly directed stream having an elongated impingement pattern extending transversely of the path of travel of the work-piece on said conveyor, an abrasive conveyor extending transversely of the path of travel of the work-piece supported on said conveyor positioned on each side of and closely adjacent to the impingement pattern produced by said stream, and inclined baffles for dividing the rebounding abrasive particles into two laterally deflected rebounding streams, which rebounding streams are directed by said baffles onto said abrasive conveyors.

3. Apparatus for blast cleaning and treating metal sheets, strips and the like comprising, a substantially horizontally extending work-piece supporting conveyor, an abrasive projector operative to fire abrasive particles at blasting velocities in a controlled downwardly directed stream having an impingement pattern extending transversely of said work-piece supporting conveyor, an abrasive conveyor extending transversely of said article conveyor positioned on each side of and closely adjacent the impingement pattern produced by said stream on the work-piece, and an inclined baffle for dividing the rebounding abrasive particles into two streams, which rebounding streams are directed by said baffles onto said abrasive conveyors.

4. Apparatus for blast cleaning and treating metal sheets, strips and the like comprising, a substantially horizontally extending work-piece supporting conveyor, an abrasive projector operative to fire a stream of abrasive particles against the work-piece supported on said conveyor, an endless belt engirdling said work-piece conveyor and the work-piece supported thereon for collecting and removing rebounding abrasive, and baffle means for directing the rebounding abrasive onto said belt.

5. Apparatus for blast cleaning and treating metal sheets, strips and the like comprising, a substantially horizontally extending work-piece supporting conveyor, an abrasive projector operative to fire a stream of abrasive particles against the work-piece supported on said conveyor, a pair of endless abrasive collecting belts engirdling said work-piece conveyor and the work-piece supported thereon so arranged as to permit the stream of fired abrasive particles to pass therebetween, and baffle means for directing rebounding abrasive onto said belts.

6. Apparatus for blast cleaning and treating metal sheets, strips and the like comprising, a substantially horizontally extending work-piece supporting conveyor, an abrasive projector operative to fire a stream of abrasive particles against the work-piece supported and advanced by said conveyor, a pair of endless abrasive collecting belts engirdling said work-piece conveyor and the work-piece supported thereon so arranged as to permit the stream of fired abrasive particles to pass therebetween, and baffle means for dividing the rebounding abrasive particles into two streams, which rebounding streams are directed by said baffle means onto said abrasive conveying belts.

7. Apparatus for blast cleaning and treating metal sheets, strips and the like comprising, a substantially horizontal work-piece advancing conveyor, a rotatably mounted centrifugal abrasive throwing wheel operative to fire abrasive particles in a downwardly directed stream having an elongated impingement pattern, means including a plurality of mechanical abrasive carrying conveyors extending transversely of the path of travel of the work-piece on said conveyor, said abrasive conveyors being located on both sides of and closely adjacent the impingement pattern produced by said stream on the work-piece, and baffle means disposed adjacent said wheel dividing the rebounding abrasive particles into two streams, said baffle means being inclined toward said abrasive conveyors whereby to direct the rebounding abrasive streams onto said abrasive conveyors.

8. Apparatus for blast cleaning metallic articles including, a housing, a substantially hori-

zontally extending conveyor for transporting the articles to be cleaned through said housing, a centrifugal abrasive throwing wheel operative to throw a downwardly directed stream of abrasive at blasting velocities against the articles transported by said conveyor, means for removing abrasive and extraneous particles loosened from the articles impinged by the abrasive stream, said means including a fan casing, a rotatable fan within said casing, a conduit leading from said casing into said housing, said conduit terminating in a laterally flared hood extending over said conveyor, said hood having downwardly inclined top and bottom walls converging toward one another to define two mouth portions of limited cross-sectional area positioned closely adjacent the article supported on said conveyor, said mouth portions meeting at an apex adjacent the midsection of said conveyor, each of said mouth portions extending diagonally with respect to the direction of movement of said conveyor to effect a flow of air along the surface of an article on said conveyor in a direction diagonally of the di-

rection of travel of said article, and a hopper in said housing and below said conveyor for receiving the spent abrasive and loosened extraneous particles removed from said articles.

9. Apparatus for blast cleaning metallic articles including a housing, a horizontally extending conveyor for transporting the articles to be cleaned through said housing, an abrasive projector operated to throw a downwardly directed stream of abrasive particles at blasting velocities against the articles transported on said conveyor, means for removing abrasive and extraneous matter from the articles impinged by the abrasive stream, said means including an endless belt encircling said conveyor and the articles supported thereon, baffle means for directing rebounding abrasive onto said belt, and means for producing a current of air moving along the surface of the articles supported on said conveyor for removing the remaining abrasive and extraneous matter from said articles not conveyed away by said belt.

ROY WILLIAM GUILTE.
